UNITED STATES PATENT OFFICE.

GEORGE S. JACOBS, OF LAPORTE, INDIANA, ASSIGNOR, BY MESNE ASSIGNMENTS, TO FINLEY P. MOUNT AS RECEIVER OF M. RUMELY COMPANY.

ENGINE-COOLING DEVICE.

1,139,289.

Specification of Letters Patent. Patented May 11, 1915.

Application filed April 30, 1913. Serial No. 764,542.

To all whom it may concern:

Be it known that I, GEORGE S. JACOBS, a citizen of the United States, residing at Laporte, in the county of Laporte and State 5 of Indiana, have invented certain new and useful Improvements in Engine-Cooling Devices, of which the following is a specification.

My present invention relates to cooling 10 devices for the cylinders and other heated parts of internal combustion engines, and has reference more particularly to that type of cooling devices wherein the engine is cooled by circulating a fluid in a jacket 15 around the cylinders and other heated parts, and thence either directly or through suitable pipes to a radiator or cooling tower or other cooling device where the heat is abstracted, the circulation being a closed 20 one and the fluid returned to the cylinder jacket to repeat the cooling function.

It is a fact suggested by theory and verified by experiment that the only practical way to abstract heat from the fluid in a 25 closed circuit cooling device is by the circulation of another cooler fluid (preferably air) through the radiator or other cooling device where it comes in contact either directly with the hot fluid from the cylinder 30 jacket or else with the walls of the pipes or chambers containing the hot fluid, abstracting heat therefrom in accordance with Newton's law of cooling, after which it must be ejected and replaced by more cooler 35 fluid. It has been found in practice that the amount of heat lost by direct radiation is practically negligible, and that it is necessary to induce a secondary circulation of a relatively cooler fluid as above stated to remove the heat from the hot fluid.

It has been found practicable, in one form of cooling apparatus, to effect this secondary circulation in the case of air by employing the exhaust of the engine in a suitable stack 45 connected with the radiator or other cooling device; and my present invention relates particularly to an improvement in that type of apparatus employing the exhaust in the case of multiple cylinder engines. Heretofore it has been the practice to lead the exhausts of the several cylinders through a

manifold into one common exhaust pipe which was led into the stack of the cooling device, where it induced a draft of cooling air which flowed through the cooling device 55 as a whole.

I have established by experiment that in the case of multiple cylinder engines a much better cooling effect can be established by dividing the stack, or both the stack and the cooling device, into sections or compartments, each section of the stack serving either the entire cooling device or a corresponding section of the cooling device. In 60 this case the exhausts of the several cylinders are not led into a common exhaust pipe, but are kept separate and led into the several compartments of the stack in such a manner that each compartment is served 65 by the exhaust or exhausts from one or more cylinders, according as the results of tests indicate the best efficiency.

My invention, its principle of operation, and the advantages secured thereby will be 70 readily understood when considered in connection with the accompanying drawing showing one practical application thereof, and in which—

Figure 1 is a vertical section through the 80 cylinders and jacket of a four-cylinder engine and the radiator thereof, showing my present improvement applied thereto. Fig. 2 is a top plan view of the radiator shown in Fig. 1. Fig. 3 is a vertical sectional view 85 of a radiator construction wherein only the stack is divided.

Referring first to Figs. 1 and 2, 5 designates the cylinders and 6 the pistons of a four-cylinder internal combustion engine, 90 said cylinders being inclosed in a water-jacket 7. 8 designates as a whole a radiator, or jacket water cooling device, herein shown as comprising a plurality of zigzag pipe sections 9 disposed side by side and connected to each other, and a casing 10 that surrounds said group of pipe sections and is open at its lower end. The casing 10 is extended upwardly in the form of a narrowed hood or stack 11. 12 designates that 100 portion of the circulation pipe that conducts the heated fluid from the cylinder

jacket 7 to one end of the water circulation system of the radiator, and 13 designates the return pipe leading from the other end of the water circulation system of the radiator back to the jacket.

In the form of the invention shown in Figs. 1 and 2, the radiator 8 is divided by transverse central partitions 14 and 15 extending from top to bottom thereof into 10 four equal compartments, and these partitions are extended upwardly through the hood 11, as shown at 14^a and 15^a.

Leading from the exhaust ports 16 of the four engine cylinders are four exhaust pipes 17, each of which leads into one of the four compartments of the hood or stack 11 and terminates in an upwardly turned nozzle 18. From this it will be apparent that the exhaust from each engine cylinder exerts a 20 suction effect through its individual compartment of the stack, inducing a current of cooling air around those parts of the water circulation pipes 9 in the radiator compartment directly therebeneath, thus 25 localizing in the radiator the effect of the exhaust of each cylinder. The greater efficiency of the described arrangement is due, as I believe, to the fact that, by creating separate exhausts through individual or 30 separate parts or sections of the radiator, a greater amount of air can be circulated through the radiator, and consequently a greater amount of heat abstracted from the hot fluid, than in the present known arrangement 35 wherein the exhausts occur with much greater frequency and each affects the entire radiator. In the arrangement illustrated it will be manifest that the exhaust actions in each compartment have only one 40 fourth the frequency that the exhaust actions would have if transmitted through a single pipe or nozzle within the stack from a manifold; and this decreased frequency is, within certain limits, more efficient than 45 the high frequency exhausts.

In Fig. 3 I show a modification wherein the radiator 8' is not partitioned, but the stack 11' alone is provided with the central transverse partitions 14' and 15' extending from the top of the stack down to approximately the upper ends of the water circulation pipe sections 9'. In this form of the invention each exhaust from any of the nozzles 18' induces an upward flow of 50 air through the entire cross-section of the radiator, but such upward flow is more pronounced, of course, through that region directly underlying the nozzle through which the exhaust occurs.

60 Although I have herein shown the radiator stack as divided into as many compartments as there are cylinders or units in the engine, with the exhaust from each cylinder leading into one of the compartments, I

do not confine my invention, in its broadest 65 aspects, to constructions wherein the stack, or the stack and underlying cooling device, are divided into exactly as many compartments as there are engine cylinders or units, since it sometimes happens that a 70 better efficiency can be secured by the employment of a less number of compartments, combining the exhausts of two or more cylinders to serve each compartment. Furthermore, as shown in Fig. 3, I do not 75 limit the invention in all cases to the presence of actual physical partitions in the cooling device itself, since frequently the construction of the cooling device is such that the use of partitions in the stack alone 80 is sufficient to largely limit the circulation induced by a particular section of the stack to the particular region of the cooling device it is designed to serve.

I claim—

1. In an engine cooling device, the combination with the cylinders and cooling jacket of a multiple cylinder engine, of a cooling device connected with said cylinder-jacket and provided with air-circulating 90 passages, a stack containing a plurality of compartments equal in number to the number of cylinders in free communication with the air-circulating passages of said cooling device, and an exhaust pipe leading from 95 each of said cylinders into only one of said compartments.

2. In an engine cooling device, the combination with the cylinders and cooling jacket of a multiple cylinder engine, of a 100 radiator containing liquid and air-circulating passages, pipes connecting said jacket and liquid circulating passages of said radiator, a stack containing a plurality of 105 compartments in free communication with the air-circulating passages of said radiator, and a separate exhaust pipe leading from each of said cylinders into one only of said compartments.

3. In an engine cooling device, the combination with the cylinders and cooling jacket of a multiple cylinder engine, of a radiator provided with air-circulating 110 passages, partitions in said radiator forming a plurality of compartments dividing the air-circulating passages of the radiator, a stack 115 divided into a corresponding plurality of compartments each communicating with a compartment of the radiator, and separate exhaust pipes each leading from each of said cylinders into one of the compartments of said stack.

4. In an engine cooling device, the combination with the cylinders and cooling jacket of a multiple cylinder engine, of a 125 radiator provided with air-circulating passages, partitions in said radiator forming a plurality of compartments dividing the air-

circulating passages of the radiator, a superposed stack containing partitions located in the same vertical planes as the partitions of the radiator and dividing said stack into a corresponding plurality of compartments, each communicating with an underlying compartment of the radiator, and a separate exhaust pipe from each of the cylinders of the engine each leading into one of the compartments of said stack.

GEO. S. JACOBS.
